UNITED STATES PATENT OFFICE.

ANTHONY ISKE, OF LANCASTER, PENNSYLVANIA, ASSIGNOR TO ISRAEL L. LANDIS, OF SAME PLACE.

SWINGING TREADLE FOR SEWING-MACHINES.

SPECIFICATION forming part of Letters Patent No. 232,130, dated September 14, 1880.

Application filed April 19, 1880. (No model.)

To all whom it may concern:

Be it known that I, ANTHONY ISKE, a citizen of the United States, residing at Lancaster, in the county of Lancaster and State of Pennsylvania, have invented certain new and useful 5 Improvements in Swinging Treadles for Sewing-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to treadles for operating sewing-machines and other mechanism.

The nature of said invention consists in the peculiar suspending and bracing devices of the said treadle, and in the construction, combination, and arrangement of the various parts of 20 my treadle mechanism, hereinafter particularly set forth and claimed.

In the accompanying drawings, Figure 1 represents a perspective view of my improved 25 treadle mechanism. Fig. 2 represents a side view of the same, and Fig. 3 represents a detail view of the treadle with its suspending-yoke and the arm attached thereto.

In said drawings, A designates the frame of 30 a sewing-machine or other mechanism to which my improved treadle is attached, the top of the said frame having been removed to show the devices hereinafter described. B designates a rod extending across the upper part of said frame, from side to side thereof, and serving 35 as a support for a yoke, C, which is sleeved thereon by means of perforated lugs formed in or on its ends, so as to allow said yoke to swing freely. Bent treadle-bar D and treadle

40 E are suspended from said yoke, said parts being cast together or rigidly connected, so that they swing as a whole on rod B when said treadle is moved backward or forward. Stops F, rigidly secured upon rod B, prevent the end-wise motion of said yoke and keep the treadle 45 in its proper position in the middle of the lower part of the machine. These stops are provided with lugs f, whereby the said rod B may be attached to the under side of the machine top

or table. When thus attached the rod need 50 not be extended from side to side of the frame.

G designates a rearwardly-extending arm rigidly connected to one end of yoke C and having its rear end pivotally attached to one end of pitman H. The other end of said pitman is similarly attached to a wrist-pin, I, 55 arranged eccentrically upon driving-wheel J.

This treadle may be operated from the knee or hip and either sitting or standing. It is especially adapted to the use of persons with stiff 60 ankles or artificial legs. The required motion of the foot and limb is a perfectly natural one. The swinging motion of the treadle thus caused is transmitted easily, through the before-mentioned connections G-H, to the wrist-pin I, 65 which, being firmly attached to wheel J, necessarily revolves about the center of said wheel and compels the rotation of the wheel itself.

The wheel may be rotated in either direction, the one chosen depending on the position of 70 the wrist-pin with respect to the center of the wheel at starting, or, more exactly, with respect to the dead-points, which are respectively a little above and behind and below and in front of the wheel center. The rotation of the wheel 75 can, of course, also be reversed by reversing the motion of the said treadle.

The yoke C obviously braces the treadle-bar D. Nevertheless, it is possible to dispense with 80 said yoke and hang the said bar directly from said rod B.

Other changes may also be made in the various parts of my treadle mechanism without departing from the spirit and scope of my invention. 85

Of course, the arm and pitman, as well as the other devices, must be of such proportions as to operate in the manner herein described.

When at rest the treadle naturally takes a slightly-forward position, so as to be convenient 90 to the foot of the operator.

If the wheel catches on a dead-point it is easily relieved by a slight backward push of the operator's foot. The treadle-bar D yields slightly to such pressure, and its elasticity 95 causes a rebound of all the devices as soon as said pressure is removed, and this frees the mechanism from the dead-lock.

Having thus fully described my invention, what I claim as new, and desire to secure by Letters Patent, is—

The combination of treadle E, curved elastic rod D, bifurcated bracing-yoke C, having perforated ends, and rigid arm G, extending obliquely downward and backward from said yoke, with rod B, having stops F and fasten-

ing-plates f, all substantially as and for the purposes set forth.

In testimony whereof I affix my signature in presence of two witnesses.

ANTHONY ISKE.
